STOCKING

Fillmore C. Rosen, Elkins Park, Pa.

Application November 7, 1951, Serial No. 17,317

Term of patent 14 years

(Cl. D47—7)

To all whom it may concern:

Be it known that I, Fillmore C. Rosen, a citizen of the United States of America, residing at Elkins Park, county of Montgomery, and State of Pennsylvania, have invented a new, original, and ornamental Design for a Stocking, of which the following is a specification, reference being had to the accompanying drawing forming a part thereof.

I claim:

The ornamental design for a stocking, as shown.

FILLMORE C. ROSEN.
